Primary Examiner — Llorellys Martinez-Rivera(74) *Attorney, Agent, or Firm* — Blank Rome LLP(57) **CLAIM**

The ornamental design for a tiara as shown and described.

DESCRIPTION

FIG. 1 is a front perspective view of a tiara of my new design;

FIG. 2 is a rear perspective view thereof;

FIG. 3 is a right side perspective view thereof;

FIG. 4 is a left side perspective view thereof;

FIG. 5 is a top view thereof;

FIG. 6 is a bottom view thereof;

FIG. 7 is a front right top perspective view thereof;

FIG. 8 is a rear left top perspective view thereof;

FIG. 9 is an enlarged view thereof, taken from portion "FIG. 9" in FIG. 1; and,

FIG. 10 is an enlarged view thereof, taken from portion "FIG. 10" in FIG. 7.

The dot-dash broken lines of FIGS. 1, 7, 9 and 10 are included to show a partially enlarged view only and form no part of the claimed design.
